UNITED STATES PATENT OFFICE.

PATRICK D. RIORDAN, OF NEW YORK, N. Y.

CLOTHES-DRIER.

1,261,622.

Specification of Letters Patent.

Patented Apr. 2, 1918.

Application filed December 12, 1916. Serial No. 136,397.

To all whom it may concern:

Be it known that I, PATRICK D. RIORDAN, a citizen of the United States of America, residing at the borough of Manhattan, in the city, county, and State of New York, have invented certain new and useful Improvements in Clothes-Driers, of which the following is a specification, reference being had to the accompanying drawings.

10 This invention relates to improvements in clothes-driers and particularly to improvements in clothes-driers adapted to be hingedly mounted on a window-ledge or like support; and an object of this invention is to provide a clothes-drier of the kind just referred to which will be simple in construction, comparatively cheap in manufacture, efficient, durable, handy and convenient in operation and use and susceptible of 20 being repaired quickly and at low cost.

In the drawings illustrating the principle of this invention and the best mode now known to me of applying that principle, Fig. 1 is a plan of the clothes-drier mounted 25 in place; Fig. 2 is a section on the line 2—2 of Fig. 1; Fig. 3 is a detail showing in plan the means for adjusting the clothes-drier relatively to the window-ledge; Fig. 4 is a section on the line 4—4 of Fig. 3; 30 Fig. 5 is a transverse section through the base-rod of the frame; Fig. 6 is a detail showing the clothesline-carrier in elevation; Fig. 7 is a section on the line 7—7 of Fig. 6; and Fig. 8 is a detail showing the clothes-35 line-carrier in plan.

In the window opening *a* in the wall *b* of the house or other building, there are mounted a window-frame *c* and a window-ledge *d*. Upon the latter, there rests a plate 40 *e* held in place by means of bolts *f* and formed with a forwardly-projecting tongue *e'* having therein bolt-holes *g*. From this plate *e*, there rise bearings *h* in which turns the shaft *i* which carries the windlass-drum 45 *j* and upon one end of which is fastened a crank *k*. The frame *m* of the clothes-drier *A* is preferably rectangular in shape and made of rod-like metal not likely to rust, *e. g.*, galvanized iron. In the window-ledge 50 *d*, there are set eye-bolts *n* in which the frame *m* is free to turn on its base *m'* which passes through the bearing *o'* formed on the outer end of the short bar *o* which is adjustably mounted on the tongue *e'* that projects forwardly from the plate *e*. The short 55 bar *o* is formed with a series of bolt-holes

g' through which and the bolt-holes *g* pass bolts *p* the upper ends of which are engaged by nuts *p'*. By loosening the latter and the bolts *f*, the position of the plate *e* 60 may be changed so as to adjust the drum *j* closer to or farther from the window. On each side *m''* of the frame *m*, there is slidably mounted a series of clothesline-carriers *r* (see Figs. 6, 7 and 8), the base or body 65 portion *r'* of which is cylindrical and shaped to fit slidably the rodlike sides *m''* of the frame *m* and from which extend the wings or cheeks *r'', r''*. One side or wing *r''* of each carrier *r* is formed with an open- 70 ing *s* opposite which there lies a finger *s'* punched from the other side or wing *r''* of the carrier *r*. Between the sides *r'', r''*, of the latter, there extends the end part of the cable *t*, which is rove over pulleys *u* rotatably mounted in sheaves or hangers *v* fastened to the crosspiece *m''* of the frame *m* 75 near each side *m''* thereof. By tightening the nut *w'* on the screw-bolt *w''*, the sides *r'', r''*, of the clothesline-carrier *r* may be 80 closed upon each other, thereby clamping the cable *t* between the sides (Fig. 7). The finger *s'* bends the cable *t* outwardly into the opening *s*, whereby and by the clamping action of its wings *r'', r''*, the carrier *r* 85 is securely fastened to the cable *t*. Each side *r'', r''*, of the carrier *r* is formed near its end with a recess *r''*, through which is rove a clothesline *w*. To permit of the ready insertion of the clothesline *w* in place 90 and to insure its retention therein, the wings *r'', r''*, are formed with reversely-disposed hooks *s'', s''* (Fig. 6). As is clearly shown in Fig. 1, the clotheslines *w* extend 95 transversely or from said to side of the frame *m*, each clothesline being supported or carried by a pair of oppositely-disposed clothesline-carriers *r*. The bight or body portion *t'* of the cable *t* is fastened to a ring *z'* of the pulley-block *z* through which there 100 is rove a rope *y* one end of which is wound around the windlass-drum *j* and the other end of which is fastened to one of the bearings *h*. When the rope *y* is wound upon the drum *j* by turning the crank *k*, the bight 105 *t'* of the cable *t* is pulled inwardly toward the wall *b* of the building and the clothesline-carriers *r* are pulled outwardly along the sides *m''* of the frame *m*, as will be obvious from an inspection of Fig. 1. To raise 110 and lower the frame *m*, a rope *z* is rove through the pulley *2* rotatably mounted in

a hanger 3 fastened to the top of the window-frame *c* (Fig. 2). The end *z'* of the rope *z* is fastened to the front crosspiece *m^x* of the frame *m*; and, after the frame *m* 5 has reached the desired position, the inner end *z''* of the rope *z* is fastened securely by winding the same upon a rope-holder *z''*. To lock the frame *m* in adjusted position, the base-rod *m'* thereof is formed with a 10 series of radial holes *m''* (Fig. 5) adapted to receive a lock-pin 4 that is passed therethrough and through holes *o''* formed in the bearing *o'* (Fig. 4).

The frame *m* being in raised position and 15 it being desired to use the clothes-drier *A*, the lock-pin 4 is removed and the inner end *z''* of the rope *z* is released from its holder *z''*, whereupon the frame *m* is allowed to swing outwardly from the vertical position 20 shown in dotted lines in Fig. 2 to the horizontal position shown in full lines in that figure, the rate of fall of the frame *m* being controlled by the housewife through the rope *z*. The lock-pin 4 is replaced in locking 25 position. When the frame *m* was raised to the vertical dotted-line position in Fig. 2, the clotheslines *w* were allowed to fall upon one another, the clothesline-carriers *r* sliding along the sides *m''* of the frame *m*; so, the 30 clotheslines *w* are now close together at the inner end of the frame *m*. The housewife fastens the wet clothes to the outermost one of the clotheslines *w* and then, by turning the crank-handle *h* of the drum *j*, she pulls outwardly the outermost or filled clothesline 35 *w*. She next fills the clothesline *w* adjacent to the outermost clothesline and, by again operating the crank-handle *h*, pulls both the filled clotheslines *w* outwardly along the 40 frame *m*. She continues thus filling successively the clotheslines *w*, working from the outermost clothesline inwardly, until the innermost clothesline has been filled. After the clothes are dried, she removes the dried 45 clothes from the clotheslines *w*, beginning with the innermost clothesline. Then, in order to throw the frame *m* into its most convenient position, she grasps the end *z''* of the rope *z*, removes the lock-pin 4 and 50 pulls the frame *m* from its full-line horizontal position (shown in Figs. 1 and 2) to the

vertical dotted-line position shown in Fig. 2. The housewife replaces the lock-pin 4; and, by engaging the end *z''* of the rope *z* with the holder *z''*, the frame *m* is fastened 5 in upright position. In order that the clotheslines *w* may not shut out any light that would pass through the window *c*, the clotheslines *w* are, by operating the windlass crank-handle *h* and permitting the windlass 10 *j* to pay out the rope *y*, allowed to fall downwardly, the clothesline-carriers *r* sliding along the sides *m''* of the frame *m*. In order that the frame *m* may not shift laterally in the eyebolts *n*, the base *m'* is provided 15 with collars *n'* (Fig. 1). For convenience of storage and transportation, the cross-pieces *m'*, *m^x*, are detachable from the sides *m''* and are fastened thereto by bolts *n''*. It may be found more convenient to mount the 20 eyebolts *n* in the wall *b*, instead of in the window-ledge *d*.

I claim:

1. A clothes-drier including a hingedly-mounted frame free to be swung up and 75 down; a bearing in which said frame is hingedly mounted, said bearing being capable of adjustment toward and from the building; pulleys carried by said frame; a cable which is rove over said pulleys; 80 clothesline-carriers slidably mounted on each side of said frame; clotheslines which extend crosswise of said frame and are carried by said clothesline-carriers; and mechanism for pulling said cable and moving said clotheslines successively along said frame. 85

2. A clothes-drier including a hingedly-mounted frame free to be swung up and down; a bearing in which said frame is mounted free to turn; a support to which 90 said bearing is fastened free to be adjusted thereon toward and from the building; and clotheslines carried by said frame.

Signed at the borough of Manhattan, city, 95 county and State of New York, this 11th day of December, A. D., 1916, in the presence of the two undersigned witnesses.

PATRICK D. RIORDAN.
